UNITED STATES PATENT OFFICE

AXEL WASBERG AND KENNETH J. TOBIN, OF CHICAGO, ILLINOIS, ASSIGNORS TO CAMEL COMPANY, OF CHICAGO, ILLINOIS, A CORPORATION OF ILLINOIS

DOOR CONSTRUCTION

Application filed February 18, 1926. Serial No. 89,001.

The present invention relates to improvements in door construction.

More particularly the present invention relates to metal doors for railway cars. A great deal of development work has been done along the line of freight car doors with the object of reducing the cost, of lessening the weight, and of improving the sturdiness thereof.

10 An object of the present invention is to provide a door which may be fabricated of relatively few parts and which will consequently be cheap and relatively simple to construct.

15 A further object is to provide a door in which the strongest parts thereof are positioned to bear the severest stresses to which the door is subjected.

20 A further object is to provide a door having a substantially flat inside surface and which will effectually prevent the creeping in of water from the outside.

25 A further object is to provide a steel door made up of relatively cheap shapes, eliminating the relatively expensive rolled shapes.

25 Further objects will appear as the description proceeds.

Referring to the drawings—

Figure 1 is a view in side elevation of a railway car having one embodiment of the 30 present invention applied thereto;

Figure 2 is a vertical section taken along the plane indicated by the arrows 2—2 of Figure 1;

Figure 3 is a view on an enlarged scale of 35 a portion of the door shown in Figure 1, but illustrating a slightly different corner construction from that shown in Figure 1;

Figure 4 is a sectional view taken along the plane indicated by the arrows 4—4 of 40 Figure 3;

Figure 5 is a fragmentary view on an enlarged scale illustrating a corner connection of one of the horizontal intermediate reinforcing members of the door as shown in 45 Figures 1 and 2;

Figure 6 is a sectional view taken along the plane indicated by the arrows 6—6 of Figure 5;

50 Figure 7 is a fragmentary view illustrating a lower corner construction;

Figure 8 is a sectional view taken along the plane indicated by the arrows 8—8 of Figure 7;

Figure 9 is a fragmentary view taken on an enlarged scale, showing a slightly modified form of corner construction;

Figure 10 is a fragmentary view of a lower corner of the door illustrating means for supporting said door from the bottom;

Figure 11 is a sectional view taken along the plane indicated by the arrows 11—11 of Figure 10;

Figure 12 is a transverse sectional view taken along the plane indicated by the arrows 12—12 of Figure 1; and

Figure 13 is a fragmentary sectional view illustrating the manner in which the present invention is applicable to a railway car having a movable post disposed intermediate of a relatively wide doorway, which type of car is frequently designated as an automobile car.

Referring first to Figure 1, the numeral 1 indicates a side wall of the car, and the numeral 2 indicates as a whole a door. The 75 door 2 is a sliding door, and according to the form illustrated in Figures 1 and 2 is supported at the top, rollers 3—3 being provided, which rollers engage with a track member 4 (Figure 2). The particular track member illustrated is the A. R. A. standard and is provided with the vertically disposed portion 5, which is secured to the car structure. Projecting outwardly from the vertically disposed portion 5, intermediate of the width of said portion 5, is the horizontally disposed portion 6, upon which the rollers 3—3 are carried. According to the structure shown in Figures 1 and 2, the rollers 3—3 are mounted upon supporting members 7, which not only perform the function of carrying the rollers 3—3, but serve as gussets, in a manner which will be referred to hereinafter. Said supporting members 7—7 not 90 only have the functions referred to, but each supporting member 7 provides supporting means for a roller 8 adapted to have rolling engagement with the under side of the horizontally disposed portion 6. The rollers 3

95

100

and 8 cooperate to hold the door in its proper vertical position.

The numeral 9 indicates a horizontally disposed rib member having the upstanding flange 10 and the downwardly extending flange 11. Said upstanding flange 10 is disposed in rear of the vertically disposed portion 5 of the track member 4, and cooperates with said vertically disposed portion 5 to limit outward movement of the door. Secured to the flange 11 of the rib member 9 is the plate 12, which plate is swedged outwardly along its lower edge for the reception of the upper flange 13 of the rib member 14, which member 14 is disposed horizontally. The front and rear edges of the plate 12 are swedged forwardly in a diagonal direction, as indicated by the numeral 12^a (Figure 12). The upper flange 13 of the rib member 14 and the lower extremity of the plate 12 are secured to the plate 15 at the upper portion of said plate 15, said plate 15, upper flange 13 and lower extremity of the plate 12 being disposed in the order named, reading from the inside of the door to the outside thereof. The intermediate portion of the plate 15 is secured to the lower flange 13 of the rib member 14. The plate 15 is substantially flat and may be of the same dimensions as plate 12, the lower extremity of the plate 15 being swedged outwardly for the reception of the upper flange 16 of the rib member 17 and the upper edge portion of the plate 18. Secured to the upper flange 16 of the rib member 17 and to the lower extremity of the plate 15 is the plate 18, the upper portion of said plate 18, the upper flange 16, and the lower extremity of the plate 15 being disposed in the order named, reading from the inside of the door to the outside thereof. The lower flange 16 of the rib member 17 is secured to an intermediate portion of the plate 18. The plate 18 may be of substantially the same dimension as plates 12 and 15, the lower portion of the plate 18 being swedged outwardly for the reception of the upwardly extending flange 19 of the horizontally disposed rib member 20. Said rib member 20 is provided with the downwardly extending flange 21, a portion of which is swedged outwardly, as indicated by the numeral 22, for cooperation with the guard members 23, which guard members are secured to the body of the car. Arranged vertically along the front and rear edges of the door are the pressed steel rib members 24 and 25, respectively. Figure 12 gives a good idea of the cross sectional contour of said members 24 and 25. It will be noted from an inspection of said figure that the member 24 has the forwardly extending flange 26 with the turned back lip portion 27, which lip portion cooperates with the pressed steel member 28, which member 28 is fastened to the body of the car. The pressed steel member 28 is provided with the lip portion 29

adapted to have sealing relationship with the lip portion 27 of the rib member 24. The member 28 is fastened to the structural steel member 30, which member 30 is provided with the filler post 31. The rib member 24 is provided with the laterally extending flange 32, which is shaped to conform to the horizontally disposed rib members 9, 14, 17 and 20 above described. In the forming operation performed upon the member 24, the portions 33 which overlie the horizontally disposed rib members may, as indicated in the drawings, be swedged to have a width slightly greater than the width of the remainder of the rib member 24, whereby to provide added bearing surface upon said horizontally disposed rib members.

The vertically disposed rib member 25 is fashioned in the manner described in connection with the rib member 24, in a number of respects, the flange 32' and the portions 33' thereof being identical with the structure discussed in connection with the rib member 24. The flange 26' of the rib member 25 is provided with the lip portion 34, which is turned inwardly of the car instead of outwardly. The rib members 24 and 25 may be identical except as regards the lip portions 27 and 34, thereby simplifying the matter of manufacture of the door. The lip portion 34 of the rib member 25 is adapted to cooperate with the pressed steel member 35, which member 35 has the lip portion 36 adapted to cooperate with the lip portion 34. Said member 35 is secured to the structural steel member 37, which member 37 is provided with the filler post 38.

The numerals 39—39 indicate reinforcing members which in practice take the form of small castings. Several of said members 39 are disposed in spaced relationship within the rib of the members 24. Rivets 40 secure said members 39—39 to the forward face of the door. Rivets 41 secure the diagonally disposed portion of the rib member 24 to said reinforcing members 39. By reason of the expedient of riveting through the diagonally disposed portion of the rib member 24 between the flange 32 thereof and the forward face, round head rivets may be used without increasing the overall transverse dimensions of the door. Inasmuch as the reinforcing members 39—39 are subjected to compressive forces, the castings referred to will be found to be well adapted for the purpose. It will be noted that the rivets 41 secure together the reinforcing members 39, the horizontally disposed sheets (12, 15 or 18), and the rib member 24.

The rib member 25 is provided with spaced reinforcing members 42—42, which may be pressed steel members shaped to conform to the space within said rib member 25. One extremity of each of the steel members 42 is riveted, by means of the rivets 44, to a trans-

versely disposed portion of the rib member 25. The other extremities of the steel members 42 are riveted, by means of rivets 43, to the diagonally disposed portion of the rib member 25, which diagonally disposed portion is indicated by the numeral 45 and lies between the flange 32 and the outer face of said rib member 25. Disposed between said diagonally disposed portion 45 and the reinforcing members 42 are the outwardly flanged edge portions, such as 12^a, of the horizontally disposed sheet metal members 12, 15 and 18. Several of said reinforcing members 42—42 are provided in spaced relationship with one another.

The corner construction at the four corners of the door may be varied considerably. According to Figures 1 and 2, the castings 7—7 serve not only for mounting the rollers 3 and 20 8, but also perform the functions of gussets, said castings being securely riveted to the adjacent portions of the rib members 9 and 24 or 25 and the adjacent plate 12. According to Figure 3, a sheet metal gusset 46 is provided which is securely riveted to the adjacent parts to form a rigid corner construction. Said gusset 46 may be used at any or 25 all of the four corners.

Figure 9 shows a corner construction 30 wherein the rib member 9 is extended over a rib to the rib member 24, said rib member 9 having a portion 46' of greater width than the remainder of the rib member 9 to provide greater bearing surface. The corner construction illustrated in Figure 9 can, of course, be used at all corners of the door.

Figures 10 and 11 illustrate a bottom supported structure, a casting 47 being provided at each lower corner of the door for supporting the roller 48, which roller 48 rides upon the track member 49 secured to the body of the car. Said casting 47 may be provided with the lip 50 cooperating with a portion of the track member 49 to limit outward movement of the door at the bottom thereof. Said casting 47 is securely riveted to the adjacent rib members and sheet metal plate, whereby to perform the functions of a gusset.

Figure 13 illustrates an embodiment of the 50 present invention applied to a car having a movable post, which car is commonly designated as an automobile car. The movable post referred to is a steel member and is indicated by the numeral 52 and has fastened thereto the filler post 51. Said steel member 52 has secured thereto the steel member 53, providing a lip portion 54 for cooperation with the lip portion 27 of the door. According to the embodiment of the invention illustrated in Figure 13, the post 51 has an auxiliary door 55 secured thereto. Said auxiliary door 55 may be of substantially the same construction as that discussed above in connection with the door 2. According to the illustrated embodiment, the rib member 56 at

the right-hand edge of the auxiliary door 55, as the parts are viewed in Figure 13, is very similar to the rib members 24 and 25, but has the plain flange 57 secured to the steel members 52 and 53. Moreover, the sheet metal plate members forming the main portion of the door has portions extended inwardly, as indicated by the numeral 58, which portions are riveted to the steel member 52.

Though certain preferred embodiments of the present invention have been described in detail, many modifications will occur to those skilled in the art. It is intended to cover all such modifications that fall within the scope of the appended claims.

We claim:

1. A steel door comprising a plurality of panels disposed in overlapping relationship with one another, each of the lower panels being disposed in rear of the panel above it, and flanged channel rib members extending across said door, each of said rib members having a flange disposed between the overlapped edge portions of said panels, certain of said panels extending across the channel rib members disposed intermediate of the height of said door and secured to the flanges of said channel rib members, said panels being bounded by a frame composed of rib members, all of said rib members being shaped and disposed to have overlapping relationship with one another and reinforcing members spaced from one another within and fastened to certain of said last mentioned rib members.

2. A steel door comprising panels, rib members forming a boundary for said panels, horizontally disposed flanged channel rib members having portions lying flat against said marginal rib members, said panels being arranged in overlapped relationship, the horizontally disposed rib members being disposed between overlapped edge portions of said panels, certain of said panels extending across channel rib members disposed intermediate of the height of said door and secured to the flanges of said channel rib members, and spaced reinforcing members within and secured to the ribs of certain of the rib members forming said boundary.

3. A steel door comprising panels, rib members forming a boundary for said panels, horizontally disposed channel rib members having portions lying flat against said marginal rib members, said panels being arranged in overlapped relationship, the horizontally disposed rib members being disposed between overlapped edge portions of said panels, certain of said panels extending across channel rib members disposed intermediate of the height of said door and secured to the flanges of said channel rib members, said panels being so disposed that each panel is disposed outwardly of the panel below it, whereby to shed moisture outwardly of said door, and spaced reinforcing members within and se-

cured to the ribs of certain of the rib members forming said boundary.

4. A sheet metal door comprising panels arranged one above another, and rib members forming the front and rear edges of said door, said rib members being provided with spaced reinforcing means within the ribs thereof, said reinforcing members, panels and rib members being riveted together.

10 5. A sheet metal door comprising panels arranged one above another, and rib members forming the front and rear edges of said door, said rib members being provided with spaced reinforcing means within the ribs

15 thereof, said reinforcing members, panels and rib members being riveted together, said rib members being provided with lip portions for sealing the front and rear edges of said door.

6. A sheet metal door comprising a plurality of panels arranged one above another, each of said panels being flanged outwardly at its front and rear edges in a direction diagonally of the main plane of said door, front and rear rib members having diagonally disposed portions lying flat against the diagonally disposed edge portions of said panels, and reinforcing members in the ribs of said rib members having portions conforming to the diagonal portions referred to, said panels, rib

30 members and reinforcing members being securely riveted together.

7. A steel door comprising a plurality of panels having overlapped relationship with one another, said panels having side portions disposed in angular relationship to the major portion thereof, each of the upper panels being disposed outwardly of the one below it, reinforcing members disposed between the overlapped edge portions of said panels, front and rear rib members having portions lying flat against said edge portions of said panels and said reinforcing members, said front and rear rib members being provided with laterally extending lip portions for sealing purposes.

45 8. A steel door comprising a plurality of panels having overlapped relationship with one another, said panels having side portions disposed in angular relationship to the major portion thereof, each of the upper panels being disposed outwardly of the one below it, reinforcing members disposed between the overlapped edge portions of said panels, front and rear rib members having portions lying flat against said edge portions of said panels and said reinforcing members, said front and rear rib members being provided with laterally extending lip portions for sealing purposes, said front and rear rib members being identical in size and shape except for the direction of said lip portions.

Signed at Chicago, Illinois, this 15th day of February, 1926.

AXEL WASBERG.
KENNETH J. TOBIN.
